Primary Examiner — T Chase Nelson*Assistant Examiner* — Kelly L Gross(74) *Attorney, Agent, or Firm* — MUNCY, GEISSLER,
OLDS & LOWE, P.C.(57) **CLAIM**

The ornamental design for a saliva test device as shown and described.

DESCRIPTION

FIG. 1 is a perspective view of a saliva test device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is a perspective view of the saliva test device in use with a lid.

The broken lines depict environmental structure that form no part of the claimed design.

1 Claim, 9 Drawing Sheets(56)
